(57) **CLAIM**

The ornamental design for a wireless headset, as shown and described.

DESCRIPTION

FIG. 1 is a top, front and right side perspective view of a wireless headset showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 2; and,

FIG. 10 is an enlarged view of portion 10 in FIG. 5.

The broken lines in the drawings illustrate portions of the wireless headset which form no part of the claimed design. The dot dash broken lines encircling portions of the wireless headset in FIGS. 2 and 5 and illustrated in enlarged views of FIGS. 9 and 10 form no part of the claimed design.
